Primary Examiner — Derrick Holland*Assistant Examiner* — Lauren Calve(74) *Attorney, Agent, or Firm* — Andrew W. Chu; Craft Chu PLLC(57) **CLAIM**

The ornamental design for a hanger loop for attachment to clothing, as shown and described.

DESCRIPTION

FIG. 1 is a top perspective view of a hanger loop for attachment to clothing showing my design;

FIG. 2 is a top perspective view thereof, shown in a closed position;

FIG. 3 is a side elevation view thereof;

FIG. 4 is an opposite side elevation view thereof;

FIG. 5 is a top plan view thereof;

FIG. 6 is a bottom plan view thereof;

FIG. 7 is a front elevation view thereof; and,

FIG. 8 is a back elevation view thereof.

The broken lines shown represent unclaimed subject matter and form no part of the claimed design.
